CLAIM

The ornamental design for a travelling bag as shown and described.

DESCRIPTION

FIG. 1 is a frontal elevated perspective view from the right side of a travelling bag in accordance with the present design.

FIG. 2 is a rearward elevated perspective view from the left side of the travelling bag in FIG. 1.

FIG. 3 is a front view of the travelling bag in FIG. 1.

FIG. 4 is a right profile view of the traveling bag in FIG. 1.

FIG. 5 is a rear view of the travelling bag in FIG. 1.

FIG. 6 is a top view of the travelling bag in FIG. 1; and, FIG. 7 is a bottom view of the travelling bag in FIG. 1.

The broken lines in the drawings show portions of the travelling bag that form no part of the claimed design.

1 Claim, 7 Drawing Sheets
